MEANS FOR SUPPORTING THE DIAPHRAGM OF A TELEPHONE TRANSMITTER OR RECEIVER

Filed July 18, 1924

HENRY JOSEPH ROUND
INVENTOR

BY *Frank J. Adams*
ATTORNEY

UNITED STATES PATENT OFFICE.

HENRY JOSEPH ROUND, OF LONDON, ENGLAND, ASSIGNOR TO RADIO CORPORATION OF AMERICA, A CORPORATION OF DELAWARE.

MEANS FOR SUPPORTING THE DIAPHRAGM OF A TELEPHONE TRANSMITTER OR RECEIVER.

Application filed July 18, 1924, Serial No. 726,693, and in Great Britain July 25, 1923.

One of the difficulties in obtaining a really accurate reproduction of sound is the difficulty in obtaining an aperiodic diaphragm.

5 If it were possible to employ a diaphragm of infinite extent and sound were allowed to impinge only upon a small area thereof, the diaphragm would be perfectly aperiodic because there would be no reflection from the edges of the diaphragm.

If again the material of which a diaphragm of limited area is constructed be self damping, then assuming that the self damping is sufficient for all wave lengths, 15 any wave force applied to the centre will be absorbed before it reaches the edge and again the result will be that there will be no resonance.

In order to obtain or approximate to such 20 result with a diaphragm formed of a material such as ebonite or steel which will not absorb all the energy due to a sound wave before it has travelled from the centre to the edge and back again, I so support a diaphragm that a slight damping is applied to the whole surface except at one part which is exposed to the air. Preferably the damping is gradual, otherwise reflection may occur at the place where an abrupt change of 25 damping occurs. For instance, I may support a large flat circular diaphragm in wool, felt or the like, leaving only a small area at the centre not so supported, the wool or the like being itself supported in a casing 30 of wood or metal. At the centre of the diaphragm may be attached a coil enclosed in a magnetic field for setting the diaphragm in vibration or for producing E. M. F. when the diaphragm is set in vibration by sound 35 waves.

In the case of a strip diaphragm a portion of the strip may be left exposed to the air while the remainder is insulated from the sound waves and immersed in a damping medium such as cotton wool or felt or even a magnetic field.

Again, I may employ a diaphragm which is not flat.

In general the total area of the diaphragm must be large compared with the 50 area exposed to the air in order that the damping edge shall not be abrupt and the total damping shall be sufficient.

My invention is illustrated by the accompanying drawing, which shows a large flat 55 circular diaphragm A supported in cotton wool B contained in a sound insulator formed of a wooden box C. The middle of the diaphragm is exposed to the air and carries a coil D in the field of a magnet E. 60 A horn F is provided in the side of the box C opposite to the middle of the diaphragm.

Having described my invention what I claim is:—

1. In a telephone transmitter or receiver, 65 a diaphragm of which only a small portion is exposed to the air and which is so supported between layers of fibrous material, whereby the reflection of vibrations is practically eliminated, substantially as de- 70 scribed.

2. In a telephone transmitter or receiver, 75 an aperiodic diaphragm consisting of a vibratory body and a fibrous body covering only a portion of each face thereof.

3. In a telephone transmitter or receiver having a diaphragm, means to support said diaphragm for aperiodic vibration, said means comprising a body of fibrous material covering a portion only of the dia- 80 phragm.

4. In a telephone transmitter or receiver, 85 a diaphragm adapted to vibrate in accordance with audible impulses, and means supporting said diaphragm to prevent resonant vibration thereof, said means being associated with a portion only of both sides of said diaphragm.

HENRY JOSEPH ROUND.
